KNITTING MACHINE

Thomas S. Hayhurst, Belle Harbor, N. Y., assignor
to Max Nydegger, Summit, N. J.

Application April 13, 1944, Serial No. 530,764

28 Claims. (Cl. 66—63)

The present invention relates to an improvement in knitting machines. Objects thereof have been to provide improved mechanism for conditioning or positioning the needle jacks in relation to the stitch cams in a links-links or knit-purl type of knitting machine, more particularly where the stitches are formed by devices operating separately from the needle positioning devices; to provide means for positioning a group or groups of needles and their corresponding needle jacks in an initial phase of the knitting cycle so that the needles may be actuated to complete the cycle by relatively simple and effective stitch cams and operating devices therefor; and to provide means more completely controllable and thus more flexible to permit a wider range of selection than that afforded by previously known machines as between needles and/or groups of needles to be rendered active or to be idled as desired.

One embodiment of my invention in a form adapted for use in an automatic multiple links knitting machine is described in the following specification and illustrated in the appended drawings in which:

Figure 1 is a view partly in plan and partly in horizontal section of a right end portion of a full automatic knitting machine embodying the improved mechanism for positioning or conditioning the needle jacks in relation to the stitch cams;

Figure 2, a fragmentary view on the line 2—2 of Figure 1 showing the control link associated with the automatic widening and narrowing control devices employed in fashioning;

Figure 3, a transverse vertical section on the line 3—3 of Figure 1;

Figure 4, an enlarged fragmentary plan view of portions of the needle beds with stitch cams, needle jacks, and needle and jack actuating devices;

Figure 5, a fragmentary view partly in vertical section illustrating the relative positions of the push-in bar and three differently conditioned push jacks, when the push-in bar is at neutral position, said push jacks being conditioned for links-links, straight knitting and for idling, respectively;

Figure 6, an enlarged fragmentary transverse vertical section on the line 6—6 of Figure 4;

Figure 7, a portion of Figure 3 further enlarged to more clearly show parts of needle jack conditioning devices;

Figure 8, an enlarged end elevation of part of the left end of the machine shown in Figure 1;

Figure 9, an enlarged plan view of parts of the left end portion of the machine shown in Figure 1

with some parts removed and some broken away;

Figure 10, an enlarged front elevation, with parts in longitudinal vertical section and other parts broken away, showing more clearly jacquard shaft actuating devices at the left end of the machine shown in Figure 1, jack positioning devices, and stitch length setting devices;

Figure 11, a transverse vertical section on the line 11—11 of Figure 10;

10 Figure 12, a transverse vertical section on the line 12—12 of Figure 10;

Figure 13, a horizontal section on the line 13—13 of Figure 12;

15 Figure 14, a graph of the periodic in and out oscillation of the push-in bar for one cycle of normal knitting;

Figure 15, a graph of the in and out motions of the front push-in bar (solid lines) and of movement of the adjustable controlling cam (dotted 20 lines) into and out of operative position for one cycle of jacquard or pattern change;

Figure 16, a graph of the in and out motions of the front push-in bar and of movements of the adjustable controlling cam into and out of operation 25 for one decking cycle wherein the operative position of the adjustable controlling cams for jacquard change (dotted line) is maintained for an extended period in decking (broken lines). Movement of the push-out bar is shown superposed on the "out" movement of the push-in bar during decking;

Figure 17, a detail of the rolling key forming part of the clutch device on shaft 243, Figure 13;

30 Figures 18, 19 and 20, fragmentary transverse sectional views of the bed plates and connecting devices showing a cycle of positioning movement of the push jack and its effect in conditioning the needle jack and needle for links-links operation;

Figures 21, 22 and 23, similar views showing a 40 cycle of positioning movement of the push jack and its effect in conditioning the needle jack and needles in the front bed for straight knitting;

Figures 24, 25 and 26, similar views showing a 45 cycle of positioning movement of the push jack and its effect in conditioning the needle jack and needles in the rear bed for straight knitting;

Figure 27, a simplified section illustrating the 50 relative positions of the parts shown when a main jack is raised by the gathering bar to condition the push jack and needle jack for links-links operation;

Figure 28, a simplified section illustrating the 55 relative positions of the parts when a main jack and corresponding push jack are conditioned for straight knitting;

Figure 29, a simplified section illustrating the relative positions of the parts with the push jack conditioned for idling the corresponding needle jack and needle;

Figure 30, a view partly in longitudinal vertical section on the line 30—30 of Figure 7 and with portions broken away and with some parts removed;

Figure 31, a horizontal section on enlarged scale on the line 31—31 of Figure 7;

Figure 32, a horizontal section on enlarged scale on the line 32—32 of Figure 7;

Figure 33, a view in front elevation and with parts broken away of the portion of the machine shown in Figure 1;

Figure 34, a fragmentary view partly in section of parts shown in Figure 7 and with a main jack raised to an intermediate needle jack conditioning position by the selector bar, the fastening bar and a lift plate; and

Figure 35, a view in elevation of a typical profile or jacquard bar.

My invention as exemplified in the drawings, includes devices for moving the needle jacks 28, Figures 4 and 6, into position to be actuated by reciprocating movement of the stitch cams 34 and 35 in knitting and for moving selected needle jacks inwardly from neutral and back in the first phase of the decking cycle. These are conveniently combined with suitable selecting devices for determining which needle jacks and needles shall be so moved, whereby the action of each needle 23 is accurately controlled to produce predetermined pattern features.

Rear push-in bar

The needle position controlling devices include, in both beds, the needle jacks 28 having end butts 29 thereon. Back of the rear bed (right, Figure 3), a rear jack push-in bar 191 is mounted on and moves forward and back with an oscillatable angle bar 192 secured to end bearing blocks 204 which slide on the upwardly exposed surfaces 204a of the frame, Figure 12.

The forwardly exposed longitudinal edge of said rear push-in bar 191 engages end butts 29 of said rear bed needle jacks 28 to advance said jacks, and needles, if any, engaged therewith, inwardly, i. e. toward the narrow space between the inner edges of the front and rear beds, Figures 18 and 19, and into position for said needle jacks 28 to be engaged and actuated by the rear stitch cam 35, Figure 6.

The rack skip slots or openings 191a, Figure 1, in said exposed edge opposite end positioned needle jacks 28 in each knitting section of the rear bed have a function in connection with racking, whereby the butts 29 of needle jacks 28 aligned with said slots are not engaged by said edge and hence are not moved inwardly when the push-in bar 191 is advanced to push the remaining jacks 28 inwardly.

Where racking over two needles, for example, takes place in a course employing less than all the needles in each section, it is clear that with the active needles conditioned for "one and one" operation, as is customary in racking, certain active needles in the rear bed will be brought into alignment with certain inactive needles at rest in the front bed. Thus, in each needle section, one active end needle in the rear bed will come opposite an inactive needle in the front bed. The next normal jack and needle positioning motion, as by a rear push-in bar 191, Figure 1, would therefore cause said active rear bed needle to be

pushed into the slot occupied by said inactive front bed needle.

To avoid this result, said bar 191 is mounted for longitudinal adjustment with the widening and narrowing devices and has portions cut away to provide slots or openings 191a, of suitable width in its front edge, the opening shown being two needles wide. In each knitting course, each of said openings 191a is maintained, by adjustment of bar 191, in position with at least a portion thereof opposite the needle bed slots holding the first two needles beyond the last needle working in the front bed.

To bring said slots 191a into proper position in widening and narrowing, said push-in bar 191 is adjustable longitudinally of angle bar 192 along with a sliding nut 191b actuated by a screw shaft 646, Figure 3, connected to widening and narrowing devices, including shaft 375, Figure 1.

Front push-in bar

In the front bed, a plurality of push jacks 193, Figures 3, 4, 7, 18, 19, 21 and 22, one in each needle groove, cooperate with and control the effective needle conditioning positions of corresponding needle jacks 28. For this purpose said push jacks 193 are actuated by a front "push-in" bar 195, mounted on an angle bar 196. Various motions are imparted to said push-in bar 195 for different purposes by cam means to be described, Figures 14, 15 and 16.

As seen in Figures 5, 7, 18 and 21, each push jack 193 has a short tapered nib 197 and a longer tapered nib 198 extending upwardly from its upper edge. By suitably adjusting its relation to push-in bar 195 when in pattern change position, each of said push jacks 193 is selectively conditioned either to escape engagement with push-in bar 195 and thus remain idle or to present one or another of said nibs for engagement by said push-in bar 195 to advance a corresponding needle jack 28 into one or another of its active stitch cam engaging positions.

In knitting successive courses without pattern change, said push-in bar 195 is moved in regular periodic sequence inwardly toward the right, Figure 14, from neutral or dwell (full line) position to the dotted line position, Figure 7, and then back to neutral. On each said inward movement of push-bar 195 the active push jacks 193 engaged thereby, either through their long nibs 198 or their short nibs 197, are similarly moved; and the corresponding needle jacks 28 are thus repeatedly positioned to be actuated by the stitch cams 34 in forming said successive courses.

In connection with jacquard changes, Figure 15, and in the decking cycle, Figure 16, push-in bar 195 has a special return movement from said dotted line position through neutral and then outward to the broken line or change position, Figure 7. This motion is faster and greater in extent than the normal periodic return to neutral (full line).

At the end of a decking cycle, Figure 16, said push-in bar 195 has a special needle positioning motion inwardly from neutral to the dotted line position Figure 7 which begins earlier and proceeds more slowly than said regular periodic inward motion. The return from this inward motion to neutral initiates the resumption of normal knitting or the regular periodic sequence above referred to.

Retractor or depressor bar

A retractor or depressor bar 194 is mounted on

said angle bar 196 in spaced relation to said push-in bar 195. During said special and more rapid motion of said push-in bar 195 outwardly to the broken line position, left Figure 7, the beveled lower edge of said retractor bar 194 moving in the same direction engages the oblique edge of long nib 198 which moves jack 193 to its extreme outer or pattern change position. Here said push jacks 193 are selectively adjustable, by suitable means hereinafter described, to control the position of nibs 197 and 198 in relation to push-in bar 195 and thus control the extent of the subsequent inward movement, if any, of said push jacks by the next inward motion of said push-in bar 195.

Needle conditioning operation of front push-in bar

On moving in from the change position reached on said greater outward motion, the push-in bar 195 selectively engages short nib 197 or long nib 198 of any given push jack 193, or neither of them, depending on whether jacquard or other suitable selecting or controlling devices shall have positioned the outer end of any such push jack 193 in its "up" (Figure 27), "middle" (Figure 28), or "down" (Figure 29) position.

When push-in bar 195 moving in from said outward position engages a push jack 193 by its short nib 197 and moves in to neutral, full line Figure 7, said push jack 193 is pushed inwardly to the A position, Figure 4, and Figure 18. Thereafter, in the knitting cycle push-in bar 195 periodically moves in to the dotted line position, Figure 7, which advances said push jacks 193 and thereby pushes the engaged needle jack 28, Figure 19, to the A' position, Figure 4, with the middle butt 30 thereof in the path of front stitch cam 34. Thus, the free end of any needle engaged by jacks 28 so advanced will be extended into a slot of the rear bed far enough to be engaged and received by a rear jack therein; and the needle will be drawn across and into said rear bed to form a stitch when said rear needle jacks 28 are actuated by the rear stitch cam 35 on a left to right stroke thereof. In said advance (A') position of needle jacks 28 in the front bed the heads or inner end portions of said jacks in both beds have cleared the inner edges of plates 826, Figure 19, and are therefore free to tilt upwardly, one to release one end of the needle and the other to receive the opposite end of the needle. If no needle is initially engaged by the head of a jack 28 in the front bed as it moves into said advance (A') position, said jack engages a needle which has been simultaneously advanced by rear push-in bar 191 in the rear bed and draws said needle into the front bed to form a stitch on a right to left stroke of the stitch cam 34. This arrangement produces the so-called "links-links" or "knit-purl" operation.

Where, on the return to neutral from said special out position, Figure 7, front push-in bar 195 has engaged a push jack 193 by its long nib 198, said jack 193 is pushed inwardly to B position, Figure 4, and Figure 21. Thereafter, in the knitting cycle, push-in bar 195 periodically moves inwardly to advance said push jack 193 and thereby pushes the engaged needle jack 28 to its B' position Figure 4, with the middle butt 30 thereof in the path of stitch cam 34, but not far enough for the free hook of needle 23 to be engaged by a needle jack in the rear bed, Figure 22. In this position, jacks 28 in the front bed are prevented from tilting vertically because their heads or in-

ner end portions are held under said cross plate 826, Figures 22 and 23. If the needle corresponding to a thus engaged needle jack 28 is in the rear bed, it will be simultaneously advanced by rear push-in bar 191 and will receive thread and form a loop by action of the needle cam in that bed. This arrangement produces "straight knitting."

Where push-in bar 195, in moving from out position to neutral, full line Figure 7, has engaged neither of the nibs 197 or 198 of any given push-in jack 193, and latter remains in idle position C, Figures 4 and 5, and is not pushed in at all by the previously described periodic in motion of bar 195 to dotted line position Figure 7. Consequently the corresponding needle jack 28 in the front bed becomes or remains idle, C' position, Figure 4; and no loop is formed on its needle 23 when the stitch cams are operated in regular knitting.

20 The selection of jacks 193 for positioning in one or another of said A, B, and C positions, Figures 4 and 5, is effected in the illustrated embodiment by the selective jack system and associated parts indicated in Figures 7 and 27 to 34 inclusive and 25 co-related with appropriate control devices which come into operation during each pattern or jacquard change phase.

20 As seen in Figures 27, 28 and 29, the conditioning of each push jack 193 when in jacquard change position is effected by a group of control jacks conveniently identified as main jack 293, connecting jack 294, interposed jack 295, and cross jack 291.

Jack conditioning for pattern effects

35 For introducing various pattern features into any given course, different needles or groups thereof may be conditioned differently. This effect is provided by actuating a profile bar, as 277, 40 Figure 35, having lugs 280 and which as seen in Figures 27 and 28 may raise the engaged main jacks 293 and therefore the outer end portions of push jacks 193 to different extents, in Figure 27 to the "links-links" conditioning position, and in 45 Figure 28 to the "straight" knitting position, depending on whether a higher (Figure 27) or a lower (Figure 28) top edge portion of profile bar 277 engages the bottom edge of main jack 293.

50 The profile bars 277 are raised by upward movement of the lifters 281 mounted on and carried upwardly by slidably mounted selector bar 502, Figure 34, which is adjusted endwise to and from different positions in connection with the operation of suitable selecting and control devices such 55 as those more fully described and claimed in my co-pending application Serial No. 530,765, and including the rocking lever 504, 507, Figure 7, operatively connected to selector bar 502 and actuated by a push rod 509, Figure 10.

60 When the pattern calls for a uniform effect across the entire row of active needles in a given course, i. e. either "links-links" or straight, all the active main jacks 293 are raised the required distance by gathering bar 327. In Figure 27, said 65 jacks 293 are shown as raised to "links-links" position and, in Figure 28, to straight position. Said gathering bar 327 is mounted to be raised and lowered by a rocking lever 328, 329, Figure 7, actuated by push rod 330 and connected parts more 70 fully described and claimed in my said co-pending application Serial No. 530,765.

Jack conditioning for fashioning

75 In fashioning, those push jacks 193 which are operatively related to predetermined end needles

are conditioned for idling, (narrowing) when in jacquard change position, Figure 29, by withdrawing the interposed jacks 295 from operative position between main jacks 293 and connecting jacks 294. For this purpose the appropriate cross jacks 291, as two at each end of the active row, are moved outwardly from their active position to idling position, as shown in Figures 7, 27 and 28, by cams 311 and 313, Figures 7 and 31. Cam 311 is mounted on a slideable block 318 secured to slide rod 321 and cam 313 on a slideable block 319, secured to slide rod 322. Cross jacks 291 are moved inwardly for widening by cam 312 on block 318 and cam 314 on block 319, Figure 31. Said slide rods 321 and 322 are actuated in one direction to produce narrowing (idling) and in the opposite direction to produce widening (restoring to active) by devices more fully described and claimed in my co-pending application Serial No. 530,766.

Each operation of narrowing in fashioning is accompanied by a decking operation. Where the narrowing includes idling of two needles at each edge, for example, stitches are transferred inwardly from a group of needles including said two idled needles to a group of corresponding number located inwardly and adjacent to said two idled needles by decker points 782 actuated in a manner to be described. Therefore, some of said control jacks are also positioned to condition the predetermined number of needles for decking in proper synchronism with the idling or narrowing steps.

To insure proper position and movement of said needles for decking purposes and regardless of any other pattern affecting condition imposed on said needles by operation of the profile bars 277 or the gathering bar 327, the push jacks 193 which control the needles in question are conditioned through the control jacks by operation of jack lifting plates, as 345, 346, Figure 30, slidably mounted in blocks 348 and 349 respectively, Figures 30 and 32. These lift plates 345 and 346, each of which imparts conditioning movement to the group of main jacks 293 at each edge of the work selected for decking, are mounted on and are moved to the extent of two needles with each step of narrowing by endwise movement of rods 350 and 351, respectively, Figures 7, 30 and 32. Said endwise movement is in part controlled and effected by the same means as those above referred to in connection with the endwise movement of slide rods 321 and 322 in narrowing and widening, and such for example as devices described and claimed in my said co-pending application Serial No. 530,766. As shown in Figures 1 and 33 slide rods 321 and 350 are moved by nut 356 threaded on shaft 360; and slide rods 322 and 351, by nut 358 threaded on shaft 361. Slide rod 351 is connected to nut 356 through arm 357.

An intermediate element employed for raising the jack lifting plates 345 and 346 in each needle bed section is the fashioning bar 341, Figures 7, 30 and 32, arranged at one side of and parallel with the profile bars 277. Extending downwardly from the bottom surface of said fashioning bar 341 are the spaced short lugs 343 for use in connection with casting off stitches in narrowing. The lifters 281 on selector bar 502 are movable, with endwise adjustment of said selector bar, into position to engage said short lugs 343. Thus, when selector bar 502 is in one of these positions and is lifted by operation of push bar 509, said lifters 281 engage lugs 343 and raise fashioning bar 341 upwardly from its down position

to a middle position with a corresponding adjustment of lifting plates 345 and 346.

The effect of raising the lifting plates 345 and 346 to middle position, Figure 34, as when the short lugs 343 of the fashioning bar 341 are engaged by the lifters 281, Figure 34, is to condition the affected push jacks 193 in middle or B position as seen in Figure 28. This insures that the needles at the edges of the work shall be moved inwardly into position to have the stitch loops removed from them by the decker points 782 which later transfer said loops to the next adjacent needles.

Decker point motions

As seen in Figure 3, the decker points 782 are mounted on carrier members each including a nut assembly 785 threaded on a right and left hand threaded screw shaft 786 and free to be tilted or rocked thereon. Rotation of said shaft causes the nuts 785 and hence the decker points 782 to be adjusted lengthwise of said shaft and of the needle bed and in synchronized relation to the narrowing and widening devices. Rotation of said shaft 786 is produced by means connected with narrowing and widening control devices, more fully described and claimed in my co-pending application Serial No. 530,766, so that the decker points may be operatively positioned in relation to end needles at all stages of narrowing and widening.

Shaft 786 and nuts 785 thereon are moved arcwise to carry decker points 782 in the general direction toward and from the needles by a rocking frame comprising spaced arms 787 in which said shaft 786 is journaled, said arms being rocked through suitable connections by cams 765 secured on decker shaft 274. A further independent tilting movement of points 782 in relation to arms 787 and combining with that produced by cams 765 is effected by cams 764 secured on decker shaft 274 and operative through suitable connecting devices supported on said arms 787. The devices above referred to for actuating decker points 782 are more fully described and claimed in my co-pending application Serial No. 530,769.

With the decking devices aforesaid properly synchronized with the previously described mechanisms, the decker points 782 are caused to move in and lift stitch loops from the needles to be decked from when the latter are moved up to advanced position in the decking cycle; to carry said loops laterally and into alignment with the next adjacent active end needles; and to move in and engage said adjacent needles to deposit the loops thereon when said needles are advanced to loop and thread receiving position in the next course.

Actuating rear push-in bar

To effect the contemplated periodic push-in function of rear push-in bar 191 simultaneously with the above described periodic "in" motion of front push-in bar 195, angle bar 192 (rear) is biased toward its "in" position by tension springs 199, Figure 8, operating through bell crank levers 200 pivoted at 201, and links 202, pivoted at 203 to said end bearing block 204, one at each end of said angle bar 192. As shown in Figure 12, each block 204 is provided with a threaded recess to receive an adjusting bolt 205 the head of which bears against a semi cylindrical rocker or pivot block 206. A set screw 207 holds bolt 205 in any desired position of adjustment.

Said rocker block 206 is positioned to pivotally engage a conforming recess provided in an upper end portion of a rear rocking lever 208 at each end of the needle bed portion of the machine and on which is pivotally mounted a cam roller 209, Figure 12. Thus, said rear rocking levers 208 are also normally biased toward "in" position by the operation of said springs 199 and, in knitting, are periodically rocked to move said rear push-in bar 191 outwardly against resistance of said springs by cams 210 secured on collars 226 by screws 227, which collars are keyed on shaft 9 in position to align said cams 210 with rollers 209, Figures 12 and 13.

The extent and timing of these periodic oscillating movements of rear push-in bar 191 in normal knitting are such as to permit free outward movement of the needle jacks in the rear bed by stitch cams 35 and to effect the periodic inward movement thereof, in proper relation to movements of said stitch cams and of devices including the needles 23 controlled by operation of the front push-in bar and suitable push jack selecting and actuating means cooperating therewith.

Said periodic oscillation of rear push-in bar 191 is arrested by cam 766, Figure 12, engaging roller 767 during a portion of the decking cycle, i. e. while selected end needles are moved into stitch transfer position, to withhold said bar 191 from its normal inward movement which is not needed at this stage because the decker devices, such as those shown in part in Figures 3 and 9, cooperate only with needles in the front bed.

Take down roller

The above described periodic to and fro movement of rear rocking levers 208 is also used in the illustrated embodiment to actuate a take down roller 211, Figure 3, mounted on shaft 214. For this purpose one end of a pivot pin 212, Figure 13, on which cam roller 209 is mounted extends inwardly to engage and deflect a lever arm 213 secured at one end of shaft 214 and thus to actuate the conventional pawl and ratchet drive indicated in Figure 3. A spring pressed pawl 265 pivoted at 266 locks shaft 214 and take down roller 211 against rotation in the wrong direction. The web of material produced by knitting is brought down between said take down roller 211, Figure 3, and a weighted idler roller 267 held in web engaging position by suitable adjustable weights 270.

Actuating front push-in bar

The front angle bar 196 is hinged at its ends to outer end portions of plates 216 mounted to slide in the machine frame, Figure 12. At the underside of each said slide plate 216 is a recess in which spaced bearing pieces 217 and 218 are mounted to slide vertically. Each provides a part cylindrical curved bearing to receive rounded upper end portions of the outer arm 219 of V shaped front rocking levers, one at each end of the needle beds, pivoted at 220. Said side plates 216, and hence said front push-in bar 195 and depressor bar 194 are reciprocated through the rocking motion of said levers.

A cam roller 221, Figure 12, is pivoted at 222 on each outer arm 219; and a cam roller 223 is pivoted at 224 on each inner arm 225 of said front rocking levers. Said cam rollers 221 and 223 on the front rocking levers are engaged and actuated respectively by identical sets of suitable cams, one set at each end of the needle beds.

Certain of said cams cooperate with said cam rollers 221 and 223 to position the needles re-

peatedly in knitting successive courses, i. e. to effect the aforesaid periodic inward motion from neutral and return to neutral of push-in bar 195. Others of said cams in each set are adjustable into and out of operative alignment with said cam rollers 221 and 223 to produce the special or additional effects incidental to decking and/or pattern changes.

Slidable cam assembly

Said adjustable cams for producing the aforesaid special or additional movements and effects are included in a slidable cam assembly, Figure 13, and are controllably adjustable into and out of operative alignment with one or the other of said rollers 221 and 223. When moved to functioning position, one of said adjustable cams, at the beginning of each pattern or jacquard change, Figures 15 and 16, effects a faster and farther outward movement of push-in bar 195 and associated parts; and another, toward the end of the decking cycle, Figure 16, effects a slower and earlier starting inward movement from neutral of said push-in bar 195 and therefore of the active needles than in normal knitting.

As shown in greater detail in Figure 13, said slidable cam assembly includes the flanged cam carrying collar 226 keyed on shaft 9 at each end 30 of the needle beds and cams thereon for effecting movement of the rear and front rocking levers respectively.

Cam 210 thereon which continuously engages roller 209 on rear rocking lever 208, to actuate 35 rear push-in bar 191 has been previously described.

"In" motion cams

An adjustable dwell cam 229 is slidably mounted 40 on said collar 226 at one side of a fixed cam 228 and is adjustably movable to and from operative position with other cams to be described. Normally, in its operative position, as shown in Figure 13, said cam 229 does not operatively engage said roller 223 during the periodic "in" and "out" motions of push-in bar 195 produced by cams 228 and 231 respectively. However, a "dwell" portion thereof engages said roller 223 to hold said push-in bar 195 in neutral position 50 between said periodic oscillations in normal knitting, Figure 14.

When cam 229 is moved inwardly as hereinafter described to disengage roller 223, cam 228 remains in engagement with said roller and effects 55 the special "in" motion of said push-in bar 195 which occurs in pattern change or jacquard operations, Figure 15 and in decking, Figure 16.

Said fixed "in" cam 228 is keyed on collar 226 in continuous alignment with roller 223 so that certain portions of said cam 228 normally engage said cam roller 223 to effect said periodic "in" motion of push-in bar 195 and thus move the active needles periodically to "in" position. This arrangement is shown in Figures 11, 12 and 13. Other portions of fixed cam 228, continuing to engage said cam roller 223 after cam 229 is disengaged therefrom, produce said special "in" motion of push-in bar 195 to neutral or dwell position from its extreme outward or jacquard change position, Figure 15.

An adjustably "in" cam 230 slidably mounted on said collar 226 at the other side of fixed cam 228 is movable into a position to engage said cam roller 223 when said dwell cam 229 is disengaged 75 therefrom and to impart to said front rocking

lever and push-in bar 195 a special "in" motion from neutral in connection with decking, Figure 16, which starts earlier and proceeds more slowly than the periodic "in" motion produced by cam 228.

"Out" motion cams

Front push-in bar 195 and retractor bar 194 are moved outwardly periodically to neutral position, Figure 14, and full lines Figure 7, by an "out" cam 231 slidably mounted on collar 226 and normally aligned to engage with cam roller 221.

For the special longer and faster outward movement beyond neutral in effecting jacquard changes, Figure 15 and for decking, Figure 16, said "out" cam 231 is displaced from cam roller 221 and the latter is engaged and actuated by slidably adjustable "out" cam 232. Thus, the adjustable "in" cams 229 and 230 and the adjustable "out" cams 231 and 232 are assembled to slide as a group longitudinally on collar 226 in relation to said fixed "in" cam 228 and the cam rollers 221 and 223.

Cam adjusting mechanism

To facilitate sliding movement of said group of adjustable cams incident to jacquard and/or decking changes, the fixed "in" cam 228 has holes parallel with its axis and in which are slidably mounted spacers or sleeves 233 longer than said holes. Bolts 234 pass through said sleeves, through corresponding holes aligned therewith in cams 230, 231 and 232 and are secured in cam 229 to clamp said sleeves between cams 229 and 230 and to secure the latter to cams 231 and 232. Means including compression springs 235 normally bias said slideable cam group toward the position shown in Figures 10 and 13 from which it is moved along said collar 226, upwardly as viewed in Figure 13, against said springs 235 by suitable actuating devices and at times and under circumstances to be described.

As shown in Figures 10, 11 and 13, a pressure ring 236 is slidably mounted on shaft 9 to bear against an adjacent thrust face on or connected with cam 232 of the group of adjustable cams above mentioned and, when actuated, to slide the cams of said group inwardly against springs 235 as described. Said ring 236 has lugs 237 which support bearing pins for a pivotal connection between said ring 236 and end portions of spaced arms 238 and 239 of a yoke fixed on a transversely extending rock shaft 240 journaled in a bearing 240a of the frame. Sliding movement of the adjustably movable cams aforesaid is effected for usual pattern or jacquard changes, Figure 15, when shaft 240 and said arms 238 and 239 are rocked in response to the actuation of suitable jacquard control devices such as shaft 256 and connected parts, Figure 11.

The position of said adjustable cams is also controlled by other means cooperating with shaft 240 to produce said special earlier starting and slower inward needle movement at the end of decking, Figure 16.

Said rocking movements of the shaft 240, at the left end of the machine, Figure 11, are transmitted therefrom to simultaneously actuate in like manner the yoke and cam assembly at the opposite or right end of the machine through levers 271, Figure 11, and 271a, Figure 1, a rod or link 272 connecting said levers, and a ball and socket connection between lever 271a and rock shaft 240b located at the right end of the machine.

Actuating the cam group shift incident to jacquard or pattern change

As shown in Figure 10, a gear 241 fixed on shaft 9 drives a gear 242 loosely mounted on jacquard actuating shaft 243. Said gear 242 forms part of a conventional clutch mechanism and, for this purpose, has a hollowed hub 244 provided with a part cylindrical recess 244a, Figure 11, opening inwardly upon the periphery of boss 247 of a cam carrier 246 secured to shaft 243. Said cam carrier 246 and said boss 247 thereof have a bearing recess 260 which is cylindrical in the carrier and part cylindrical in the boss, said boss portion being open outwardly into the annular path of rotation of the opening of recess 244a on hub 244.

Said hub 244 is releasably connected to rotate said cam carrier 246 and jacquard shaft 243 by means including a rolling key, Figure 17, having a cylindrical body or bearing portion 245 mounted in the cylindrical recess 260 of carrier 246, a reduced bearing end 245b extending into the part cylindrical portion of said recess 260 in boss 247, and a trip arm 245a extending outwardly from the cylindrical portion of recess 260 through a radial slot 246a in carrier 246, Figure 10.

Said rolling key is mounted to rock in said cylindrical recess 260 of said cam carrier and with the outer end of its arm 245a extending beyond slot 246a and in position to be engaged by and disengaged from a trip lever 252.

An arcuate cam 248 having tapered ends extends laterally from one side of cam carrier 246 in position to engage a cam roller 249 on an arm 250 secured to rock shaft 240. When said carrier 246 is rotated with shaft 243 from said gear 242 through the clutch, cam 248 rocks shaft 240, arms 238 and 239, and arm 276 thereon from their normal positions, Figure 11, to deflected or operative positions.

Rotation of jacquard actuating shaft 243 is also utilized in the illustrated embodiment to actuate portions of jack selecting devices when gear 242 is operatively connected to transmit rotation thereto from gear 241 through the rolling key clutch device above described.

In normal stitch forming operation of the machine, hub 244 of gear 242 rotates freely counter-clockwise, Figure 11, around boss 247 carrying recess 244a past the reduced bearing end 245b of the rolling key. In this phase, trip arm 245a thereof is held in retracted or non-connecting position against resistance of a spring 251 by an end portion of lever 252 (full line position, Figure 11) which is pivoted at 253 and biased toward said position by a spring 254. However, spring 254 exerts relatively light tension on lever 252 compared to the expansion energy of a stronger spring 251 which is applied directly against trip arm 245a, and biases said arm toward the extended or clutch operating position (broken lines). Accordingly, at the point in rotation of hub 244 where the recess 244a thereof comes between recess 260 in boss 247 and the adjacent outer end of lever 252, said end would be deflected from the full line position, Figure 11, by the extension of said spring 251, acting through trip arm 245a except that the lower end of said lever 252 is normally blocked by a detent arm 255 fixed on jacquard control shaft 256. Said arm 255 has a detent lug 257 at its end, Figure 10, which releasably engages a terminal extension or lug 258 on lever 252. A fixed stop 259 limits the

extent of downward swing of the lower end of lever 252, Figure 11.

When operation of Jacquard actuating shaft 243 is required for the purposes above indicated, control shaft 256 is rotated by suitable means to one of various positions in either direction from the full line position shown in Figure 11. The extent and direction of such rotation beyond the two positions shown in broken lines depend on considerations incident to jack selection and are not here pertinent. Said rotation, however, causes detent lug 257 on arm 255 to clear and thus release extension lug 258 of lever 252. Lever 252 is now biased against the outer end of trip arm 245a by spring 254; but said key cannot rotate in its bearing recess 260 until recess 244a in the hub 244 of gear 242 comes opposite said recess 260 and the reduced extension 245b of the key.

At that point in the normal rotation of said gear 242 and its hub 244, expansion spring 251 bearing outwardly against trip arm 245a causes said key to rotate against the relatively weak resistance of spring 254 as applied through lever 252. This rotation of said key tilts the reduced partly cylindrical extension 245b into the broken line position, Figure 11, so that a portion thereof now extends into recess 244a thus bringing boss 247 and consequently carrier 246 into driven connection with gear 242.

This operative connection and the consequent rotation of shaft 243 carry trip arm 245a beyond the key engaging end of said lever 252 which immediately snaps back to full line position where it may be again locked by arm 255 and where, at the end of one turn of said shaft, it may again engage trip arm 245a to release the clutch. Said arm 255 is returned to locking position, full line Figure 11 by reverse operation of control shaft 256.

During said single rotation of said jacquard operating shaft 243 and cam carrier 246 thereon, effected as above described, the arcuate cam 248 is revolved with said carrier to engage cam roller 249 on arm 250. This tilts and holds the arms 238 and 239 inward (toward the right, Figure 10), and effects a corresponding sliding movement and repositioning of the above described slidably adjustable cams as a group to an advanced or operative position on collar 226 where they are held during rotation of shaft 243 for a substantial portion of the jacquard change cycle, Figure 15. Similar operation of like parts takes place simultaneously at the other end of the machine.

Operative effect of shifting cams

In said advanced position of said groups of adjustable cams, a portion of the adjustable "out" cam 232 comes into engagement with front arm roller 221 and, in rotating, swings front arm 219 farther out, or to the right, Figure 13, than when roller 221 is engaged only by the normally operative "out" cam 231. This moves the front push-in bar 195, the retractor bar 194, and the push jacks 193 outwardly from neutral, full lines Figure 7, to their extreme extended or pattern changing position, Figure 15 and broken lines, Figure 7.

Any desired or necessary repositioning of suitable "control" devices to vary the operative position of selected ones of the push jacks 193 is completed when push-in bar 195 and the associated push jacks 193 are in this "out" position. The next inward motion to neutral (full line Figure 7) of said front push bar 195, retractor bar

194 and push jacks 193 from said extreme out or jacquard change position is effected by cam 228 while said arcuate cam 248, Figure 11, is engaging roller 249 to hold adjustable cam 229 out of engagement with cam roller 223.

The above described cycle of out and in movements of push-in bar 195 and the interposed jack selecting and repositioning operation incident thereto, are timed to occur during the knitting course immediately preceding that in which the results of the pattern changes are to be incorporated.

Special in-motions of front push-in bar in decking

The operation of "decking" on the illustrated machine starts with a preliminary jacquard change, Figure 15, effected during the last preceding knitting course and whereby the push jacks 193 are conditioned for advancing predetermined end needles, as previously described, are moved in by operation of cam 228 and push-in bar 195 from broken line position of the latter, Figure 7, to neutral, as B, Figures 4 and 21 as above described.

In the next phase of the "decking" cycle, Figure 16, those end needle jacks 28 which are engaged by said selected push jacks 193 are advanced by the further inward movement of push-in bar 195 actuated by cam 228, from full line to dotted line position, Figure 7, to move said needle jacks and their needles to the "straight" position B', Figures 4 and 22, where the needle hooks are engaged by the advanced decker points 782 which lift the stitch loops therefrom and later deposit them on adjacent active needles in the manner previously described. Rear push-in bar 191 is held in retracted position during this "in" movement of front push-in bar 195 by cam 766 on decker shaft 274.

During the subsequent "out" movement of said push-in bar 195 and for the remainder of the decking cycle, operation of the stitch or draw cams 34, 35 and of the repositioning cams 34', 35', Figures 4 and 6, is arrested. For this purpose, rotation of stitch cam drive shaft 16 is stopped by releasing a clutch, indicated generally at 13, 14, Figure 1, by suitable means actuated from a decker control shaft not shown.

Push-out bar

Continuing with the decking cycle, the needle jacks 28 of the selected needles from which the stitches are transferred in decking are now returned to neutral or idle position, Figure 21, and C', Figure 4, by push-out bar 775, Figures 6 and 9, which is moved outwardly to broken line position, Figure 6, by endwise thrust of plunger 773, Figure 9, actuated by cam 768 mounted on cam carrier 273a on decker shaft 274 through suitable connections as shown, including a bell crank 770 and a cam roller 769 thereon, Figure 11.

With said outward movement of push-out bar 775, front push-in bar 195 is moved outwardly again by cam 232 to its jacquard change or extreme "out" (broken line) position, Figure 7. The relative timing of said in and out motions of push-in bar 195 and the out motion of push-out bar 775 in a typical decking cycle are represented graphically in Figure 16 by the corresponding movements of their several actuating cams.

Actuating push-out bar

Said cam carrier 273a has said push-out bar actuating cam 768 extending outwardly therefrom and movable upon rotation of said carrier into and out of engagement with cam roller 769 on bell crank 770. As seen in Figure 9, one arm of said bell crank has a handle 771 and a socket 772. The rounded outer end of a plunger 773 engages said socket 772. The flat inner end face 774 of said plunger bears against the outer end of the "push-out" or draw bar 775 extending substantially the length of the front cam housing 36 and supported adjacent to portions of the under surface thereof. Said bar is provided with sets of spaced bar retaining plates 781 and 781a having opposed oblique guide faces.

As shown in Figure 9, said front cam housing 36 is provided with an oblique slot 776 at each end to receive a pin 777 mounted on said slide plate 781a. A spring 778 connects pin 777 with a relatively fixed pin 779 mounted on said housing 36 and biases said bar 775 toward the retracted position shown in Figure 9.

Said bar 775 is supported and its direction of movement determined by obliquely disposed flanged plates 780 engaging flanges on retaining plates 781a and secured to a portion of the under surface of the top wall of said housing 36 adjacent to slots 776. Each of said guide plates 780 is embraced by and between said opposed oblique faces of plates 781 and 781a on "push-out" bar 775.

Through the connections just described, spring 778 normally biases said "push-out" bar toward "in" position, Figures 3 and 9 and, solid line, Figure 6. However, when cam 768 engages cam roller 769 during rotation of decker shaft 274, or if bell crank 770 is actuated to like effect by hand, plunger 773 is thrust inwardly against resistance of spring 770a and imparts oblique end-wise and outward movement to "push-out" bar 775, Figure 16. The latter engages any jack end butts 29, Figure 6, which may be in its path; and, in moving outwardly to the dotted line position there shown, withdraws the corresponding needle jacks 28 and any needles thereby engaged to their initial retracted positions. Push-out bar 775 is returned to normal retracted position by operation of springs 778 as soon as bell crank 770 is restored to inoperative position by spring 770a, which occurs when cam 768, rotating with shaft 274, is moved past the point of engagement with roller 769.

While said push-in bar 195 is in said jacquard change position, the last actuated end needles are idled by narrowing; the remaining active needles are conditioned to produce any desired pattern effect in the next course; and the end needles are conditioned to receive loops transferred by the decker points 782 from said last idled end needles.

Thereupon, the remaining active push jacks 193 are advanced by "in" motion of push-in bar 195 actuated by cam 228 to neutral position as A and/or B, Figure 4.

Special slower in motion of push-in bar

As a preliminary to resumed knitting and as the final decking step, all of said push jacks 193 including those conditioned to receive the transferred loops are advanced by a further inward motion of said push-in bar 195 actuated by cam 230, Figure 16, beginning earlier and proceeding more slowly than its normal periodic "in" motion to bring said push-in bar 195 to the usual

"in" position periodically produced by cam 228 in knitting.

This advance of said push-in bar 195 and push jacks 193 carries the corresponding active needle jacks 28 and the hooks of the needles engaged thereby to the A' or B' positions, Figure 4, depending on the jacquard setting. This slower "in" motion of bar 195 enables the hooks of the needles at each end of the row or section of active needles to move relatively slowly through the several stitch loops which are held by the decker points, after a proper lateral movement thereof, in position to be received on said hooks, whereupon said loops are deposited on said hooks and the decker points are quickly withdrawn. Rear push-in bar, resuming regular operation, moves inwardly in a normal manner during the last described special "in" motion of front push-in bar 195.

20 For this special earlier starting, longer and slower "in" motion of bar 195 incident to the end of decking and, in effect, forming also an initial part of the needle positioning operation for the next knitting course, said adjustable "in" cam 230 is retained in engagement with cam roller 223, Figure 16, while cam 229 remains disengaged therefrom during a longer period than that usually required for effecting jacquard change and terminating substantially with resumed knitting of the next course.

This prolonged engagement of cam 230 with cam roller 223 is effected by operation of a cam 213, Figure 10, projecting inwardly from cam carrier 273a mounted on decker shaft 274, Figure 11, in a position to engage a cam roller 275 mounted on arm 276 secured on shaft 240. Effective engagement occurs at or before the time when said arcuate cam 248 normally disengages from roller 249 after a usual jacquard change operation, Figure 15. In effect said arm 276 remains in deflected position as previously noted; and cam 273 by moving into operative position, prevents return of said arm 276, and therefore of the group of adjustable cams, including cam 230, to normal inoperative position, Figures 11 and 16, which, except in decking, occurs simultaneously with disengagement of roller 249 from arcuate cam 248 toward the end of an ordinary jacquard change cycle, Figure 15.

50 The mechanism embodying my invention as above described provides effective and reliable needle positioning means well adapted for use in the flat bed type of knitting machine. These improved constructions and combinations are 55 novel and particularly useful in the operation of a multiple flat bed machine provided with decking, fashioning, and/or pattern change devices actuated in whole or in part through automatic controls.

60 The above described mechanisms are also shown and described but not independently claimed in my co-pending application Serial No. 530,761 filed herewith and of which the present application is in effect a division.

65 I claim:

1. In a links-links knitting machine having opposed needle beds, needles and needle jacks mounted therein, and needle jack engaging and actuating cam means operatively related to each 70 needle bed for moving needle jacks therein toward idle position, the combination of push jacks arranged and adapted to engage needle jacks of one of said needle beds to condition said needle jacks for engagement with the cam means operatively related to that needle bed, means mounted 75

to reciprocate in the direction of movement of said needle jacks and arranged and adapted to engage and actuate said push jacks, and means arranged and adapted to reciprocate toward and from said push jack actuating means and to engage and advance needle jacks of the other of said needle beds inwardly from neutral to a position for engagement thereof by the cam means operatively related to said other needle bed.

2. In a links-links knitting machine having opposed needle beds, needles and needle jacks mounted therein, and needle jack engaging and actuating cam means operatively related to each needle bed for moving needle jacks therein toward idle position, the combination of push jacks arranged and adapted to engage needle jacks of one of said needle beds to condition said needle jacks for engagement with the cam means operatively related to that needle bed, a reciprocatable push-in member arranged and adapted when moving in one direction to engage and move said push jacks inwardly to needle jack conditioning position, a retractor member reciprocatable with said push-in member and arranged and adapted to move said push jacks outwardly, and means arranged and adapted to engage and advance needle jacks of the other of said needle beds inwardly from neutral to a position for engagement thereof by the cam means operatively related to said other needle bed.

3. In a links-links knitting machine having opposed needle beds, needles and needle jacks mounted therein, and needle jack engaging and actuating cam means operatively related to each needle bed for moving needle jacks therein toward idle position, the combination of push jacks arranged and adapted to engage needle jacks of one of said needle beds to condition said needle jacks for engagement with the cam means operatively related to that needle bed, a push-in bar for advancing said push jacks inwardly, a retractor bar for withdrawing said push jacks from advance position, a push-in bar for advancing needle jacks of the other of said needle beds inwardly, a drive shaft, and means operatively interposed between said shaft and said push-in bars to effect inward movement thereof.

4. In a links-links knitting machine having opposed needle beds, needles and needle jacks mounted therein, and needle jack engaging and actuating cam means operatively related to each needle bed for moving needle jacks therein toward idle position, the combination of push jacks arranged and adapted to move needle jacks of one of said needle beds inwardly from neutral to a position for engagement by the cam means operatively related to that needle bed, a push-in bar for advancing said push jacks inwardly, a retractor bar for withdrawing said push jacks from advanced position, a push-in bar for advancing needle jacks of the other of said needle beds inwardly, spring means for retracting said last mentioned bar from advanced position, a drive shaft, and means operatively interposed between said shaft and said push-in bars to effect inward movement of said bars.

5. In a links-links knitting machine having opposed needle beds, needles and needle jacks mounted therein, and needle jack engaging and actuating cam means operatively related to each needle bed for moving needle jacks therein toward idle position, the combination of a reciprocatably movable push-in member, push jacks arranged and adapted to engage needle jacks of

one of said needle beds, each of said push jacks having a plurality of longitudinally spaced engagement surfaces and being adjustably mounted to bring one or another of said surfaces into the path of movement of said push-in member, and means for actuating said push-in member while the latter engages one or another of said engagement surfaces of said push jacks to advance corresponding needle jacks inwardly from neutral into one or another of different cam means engaging positions depending on which of said engagement surfaces of the push jacks is engaged by the push-in member.

6. In a links-links knitting machine having opposed needle beds, needles and needle jacks mounted therein, and needle jack engaging and actuating cam means operatively related to each needle bed for moving needle jacks therein toward idle position, the combination of a reciprocatably movable push-in member, push jacks arranged and adapted to engage needle jacks of one of said needle beds, each of said push jacks having a plurality of spaced nibs of different length and being adjustably mounted to bring one or another of said nibs into the path of movement of said push-in member, and means for actuating said push-in member while the latter engages one or another of said nibs.

7. In a knitting machine having a needle bed, needles and needle jacks mounted therein and movable between idle and advanced positions, cam means operative in knitting for imparting stitch forming movement to said needle jacks when the latter are in an advanced position and to move said needle jacks toward idle position, and decking devices arranged and adapted to receive stitch loops from needles actuated by certain of said needle jacks when the latter are in advanced position, the combination of push jacks arranged and adapted to move said certain needle jacks inwardly from idle position to advanced position, and means operating independently of said cam means to move said certain needle jacks outwardly to idle position.

8. In a knitting machine having a needle bed, needles and needle jacks mounted therein, said jacks each having an end butt and a middle butt, cam means operative in knitting and arranged to engage said middle butts to move said needle jacks toward idle position, and decking devices arranged to receive stitch loops from needles actuated by certain of said needle jacks when the latter are in advanced position, the combination of push jacks arranged and adapted to move needle jacks inwardly from idle position to said advanced position, and means operating independently of said cam means and engaging said end butts to return said certain needle jacks to said idle position.

9. In a knitting machine having a needle bed, needles and needle jacks mounted therein and movable between idle and advanced positions, cam means operative in knitting and arranged and adapted to move said needle jacks from advanced position toward idle position, and decking devices arranged and adapted to receive stitch loops from needles actuated by certain of said needle jacks when the latter are in advanced position, the combination of push jacks arranged and adapted to engage said certain needle jacks, a shaft, cam means thereon, means actuated by certain of said cam means for advancing said push jacks inwardly from neutral and by other of said cam means for returning said push jacks to neutral, a second shaft operatively connected

with said decker devices, and cam means on said second shaft arranged and adapted to effect the return of said certain needles from decking to idle position.

10. In a knitting machine wherein the needle jacks are periodically advanced in knitting from idle position to active position and are returned to idle position by reciprocating cam means; and wherein, in decking, certain of said needle jacks are controllably advanced from idle to active decking position by the same means employed in said periodic advance, the combination of means operative independently of said reciprocating cam means to engage said certain needle jacks and move the same to idle position after said advance thereof to active decking position, means for actuating said needle jack engaging means, and means for arresting operation of said reciprocating cam means during said movement of said certain needle jacks to idle position incident to decking.

11. In a knitting machine wherein the needle jacks in one bed thereof are advanced to operating position by inward movement of a push-in bar from its neutral position and are returned to inactive position by cam means movable transversely of said inward movement, and push jacks are interposed between said push-in bar and said needle jacks and are advanced inwardly by said inward movement of said push-in bar and retracted on outward movement thereof to its neutral position, the combination of means for moving said push-in bar and said push jacks outwardly from said neutral position to a pattern change position, means for adjusting the operative positions of said push jacks in relation to said push-in bar while in said pattern change position, and means for returning said push-in bar and said push jacks inwardly to said neutral position.

12. In a knitting machine wherein the needle jacks in one bed thereof are advanced to operating position by inward movement of a push-in bar from its neutral position and are returned to inactive position by cam means movable transversely of said inward movement, and push jacks are interposed between said push-in bar and said needle jacks and are advanced inwardly by said inward movement of said push-in bar and are retracted on outward movement thereof to neutral position, the combination of cam means for periodically effecting said inward movement of said push-in bar from neutral, and other cam means adjustable into and out of operative relation to said push-in bar and arranged and adapted to impart thereto when in said operative relation a special inward movement which starts earlier and proceeds more slowly than said periodic inward movement thereof effected by the first mentioned cam means.

13. In a knitting machine having a needle bed, needle jacks and needles therein, and decking devices including a decker actuating shaft, the combination of push jacks, a push-in bar engaging said push jacks and movable in one direction to periodically advance them inwardly toward said needle jacks, a retractor bar engaging said push jacks and movable with movement of said push-in bar in the opposite direction to move said push jacks outwardly away from said needle jacks, cam means operatively connected to periodically actuate said push-in bar inwardly, cam means adjustable into operative relation to said push-in bar to impart thereto an inward motion which begins earlier and proceeds more

slowly than said periodic advance movement thereof, and means operatively connected to said decker actuating shaft for moving said adjustable cam into and out of said operative relation to said push-in bar.

14. In a knitting machine having a needle bed, needle jacks and needles therein, a stitch cam, fashioning devices including means for narrowing the work being knitted, push jacks for moving the needle jacks into operative stitch forming position in relation to the stitch cam, decking devices including decker points movable into and out of stitch transferring relation to end needles operating at end portions of the work being knitted, the combination of a push-in bar operatively engaging said push jacks and movable inwardly to advance the needle jacks of said end needles into decking position, and a push-out bar operatively connected with said decking devices and movable outwardly to return said end needle jacks from said decking position.

15. In a knitting machine having a needle bed, needle jacks therein, and push jacks mounted to engage said needle jacks, the combination of a push-in bar supported to move above said needle bed and to engage said push jacks, means for moving said push-in bar inwardly across said needle bed from a dwell position, and means for moving said push-in bar outwardly across said needle bed to said dwell position.

16. In a knitting machine having a needle bed, needle jacks therein, push jacks mounted to engage said needle jacks and adjustable in relation to each other and to said needle bed to effect pattern variations in the knitted product, the combination of a push-in bar supported to move above said needle bed and to engage said push jacks, means for adjustably moving said push jacks, means for moving said push-in bar outwardly from said needle bed into position to engage the adjusted push jacks, and means for moving said push-in bar and said push jacks inwardly toward said needle bed.

17. In a knitting machine having a needle bed, needle jacks therein, and push jacks mounted to engage said needle jacks, the combination of a push-in bar supported to move above said needle bed and to engage said push jacks, means mounted in continuous operative position and adapted for moving said push-in bar inwardly across said needle bed from dwell position, means adjustable into and out of operative position for moving said push-in bar inwardly across said needle bed from dwell position, and means for effecting adjusting movement of said adjustable means.

18. In a knitting machine having a needle bed, needle jacks therein, and push jacks mounted to engage said needle jacks, the combination of a push-in bar supported to move above said needle bed and to engage said push jacks, a cam shaft, a cam mounted thereon and operatively connected to said push-in bar to effect inward movement thereof across said needle bed from dwell position, and a cam slidably mounted on said cam shaft and operatively connected to said push-in bar to effect outward movement thereof across said needle bed to said dwell position.

19. In a knitting machine having a needle bed, needle jacks therein, and push jacks mounted to engage said needle jacks, the combination of a push-in bar supported to move above said needle bed and to engage said push jacks, a cam shaft, a cam mounted thereon and operatively connected to said push-in bar to effect inward move-

ment thereof across said needle bed from dwell position, a cam slidably mounted on said cam shaft and operatively connected to said push-in bar to effect outward movement thereof across said needle bed to said dwell position, and means including a cam slidably mounted on said cam shaft and operatively connected to said push-in bar to maintain said push-in bar in dwell position between said outward and said inward movements thereof.

20. In a knitting machine having a needle bed and needle jacks therein, the combination of push jacks mounted in said needle bed and having inner end portions arranged to engage said needle jacks and outer end portions extending outwardly from said needle bed, means for moving said push jacks outwardly to bring said outer end portions into a jacquard change position, means effective while said push jacks are in jacquard change position to change the operative relation thereof to said needle jacks, and means for moving said push jacks inwardly from said jacquard change position to neutral or dwell position.

21. In a knitting machine having a needle bed and needle jacks therein, the combination of push jacks mounted in said needle bed and having inner end portions arranged to engage said needle jacks and outer end portions extending outwardly from said needle bed, means for moving said push jacks outwardly to bring said outer end portions into a jacquard change position, means effective while said push jacks are in jacquard change position to change the operative relation thereof to said needle jacks, means for moving said push jacks inwardly from said jacquard change position to neutral or dwell position, and means for moving said push jacks inwardly from said dwell position to engage and advance said needle jacks inwardly.

22. In a knitting machine having a needle bed and needle jacks therein, the combination of push jacks mounted in said needle bed and having inner end portions arranged to engage said needle jacks and outer end portions extending outwardly from said needle bed, means for moving said push jacks outwardly to bring said outer end portions into a jacquard change position, means effective while said push jacks are in jacquard change position to change the operative relation thereof to said needle jacks, means for moving said push jacks inwardly from said jacquard change position to neutral or dwell position, a cam shaft, a cam fixed thereon and operatively connected normally to move said push jacks inwardly from said dwell position to engage and advance said needle jacks inwardly, an adjustable cam slidably mounted on said cam shaft, and means for moving said adjustable cam along said cam shaft into operative position to advance said push jacks inwardly from said dwell position in a movement beginning earlier and progressing more slowly than said normal inward movement thereof effected by said fixed cam.

23. In a knitting machine having a needle bed, needles and needle jacks therein and push jacks mounted in said needle bed to engage said needle jacks to move the same inwardly, the combination of a push-in bar mounted to engage said

push jacks, a retractor bar operatively connected to move with said push-in bar and to engage said push jacks, a main cam shaft, means mounted on said cam shaft and operatively connected to move said push-in bar, said retractor bar and said push jacks inwardly and outwardly, a repositioning bar mounted to engage said needle jacks, a second shaft, and cam means mounted on said second shaft and operatively connected to said repositioning bar to move the same and said needle jacks outwardly.

24. In a knitting machine, the combination of a needle positioning push jack, a push-in bar arranged and adapted to impart needle positioning movement thereto, means for actuating said push-in bar, said push jack having a nib extending therefrom toward the path of movement of said push-in bar, and means for varying the position of said push jack to bring said nib into and out of the path of movement of said push-in bar.

25. In a knitting machine, the combination of a needle positioning push jack, a push-in bar arranged and adapted to impart needle positioning movement thereto, means for actuating said push-in bar, said push jack having spaced nibs extending therefrom toward the path of movement of said push-in bar, and means for varying the position of said push jack to bring one or another of said nibs into and out of the path of movement of said push-in bar.

26. In a knitting machine, the combination of a needle positioning push jack, a push-in bar movable in the direction of positioning movement of said push jack, said push jack having different portions adapted to be engaged by said push-in bar to effect different positions of a needle, and means for differentially positioning said push jack in relation to said push-in bar whereby one or another of said different portions of the push jack may be brought into position to be engaged by said push-in bar to impart needle positioning movement to said push jack.

27. In a knitting machine, the combination of a needle positioning push jack, a push-in bar, means arranged and adapted to move said push-in bar in one direction from neutral position to engage and impart needle positioning movement to said push jack, means arranged and adapted to move said push-in bar in the opposite direction to a change position, means for returning said push jack to neutral position, and separate means for moving said push jack from said neutral position to said change position.

28. In a knitting machine, the combination of a needle positioning push jack, a push-in bar, means arranged and adapted to move said push-in bar in one direction from neutral position to engage and impart needle positioning movement to said push jack, means arranged and adapted to move said push-in bar in the opposite direction to a change position, means for returning said push jack to neutral position, and a retractor bar operatively connected to and movable with said push-in bar and arranged and adapted to engage said push jack to move the same from said neutral position to said change position.

THOMAS S. HAYHURST.
